INFANT BATHING AND DRESSING TRAY

Gregory O'Brien and Mary Jane O'Brien, both of 613
N. La Sera Ave., West Covina, Calif.

Filed Nov. 2, 1959, Ser. No. 58,150

Term of patent 14 years

(Cl. D5—5)

FIG. 1

FIG. 2

FIG. 3

FIG. 2 is a side elevational view thereof, partly in section;

FIG. 3 is a top plan view thereof; and

FIG. 4 is an end elevational view thereof, partly in section.

We claim:

The ornamental design for an infant bathing and dressing tray, as shown.
